UNITED STATES PATENT OFFICE.

WILLIAM TAYLOR; OF DETROIT, MICHIGAN.

DESIGN FOR A HINGE.

SPECIFICATION forming part of Design No. 30,954, dated June 6, 1899.

Application filed December 21, 1897. Serial No. 662,938. Term of patent 7 years.

To all whom it may concern:

Be it known that I, WILLIAM TAYLOR, a citizen of the United States, residing at Detroit, county of Wayne, State of Michigan, have invented and produced a new and original Design for a Hinge; and I declare the following to be a full, clear, and exact description of the invention, such as will enable others skilled in the art to which it pertains to make and use the same, reference being had to the accompanying drawings, which form a part of this specification.

Figure 1 is a plan view. Fig. 2 is a side elevation.

15 A, B, and C indicate leaves of a hinge. The leaf A has at its extremity a nearly-round button having a nearly half-globular boss on one side. From one side of the button a neck b extends and bends to nearly a right angle. 20 From the angle the leaf extends to the joint. There this part terminates with a nearly-globular head b'. At one side of the head b' is a head c of a second leaf C, and at the other side of the head b' is the head d of the third leaf D. The leaf C is sharply angled at c²,

and between the angle c² and the head c the body of the leaf is round in cross-section. The other branch c³ of the leaf C is flattened on one face and curved on the other. The angles of the two bent leaves are so arranged that when the leaf D lies parallel to the branch c³ of the leaf C the parts c' extend parallel to that part of the leaf B which lies between the angle and the head b'. 30

That part of the hinge which is immediately 35 around the pintle presents the appearance of three balls or globes with slightly-flattened faces at their place of contact. A stem extends from the middle ball to the circular button a, and from the ball at one side extends a 40 bent leaf and from the other a straight leaf.

What I claim is—

The design for a hinge, substantially as shown and described.

In testimony whereof I sign this specifica- 45 tion in the presence of two witnesses.

WILLIAM TAYLOR.
